UNITED STATES PATENT OFFICE.

WILLIAM A. DOBLE, OF SAN FRANCISCO, CALIFORNIA, ASSIGNOR TO THE PELTON WATER WHEEL COMPANY, OF SAN FRANCISCO, CALIFORNIA, A CORPORATION OF CALIFORNIA.

SPEED-GOVERNOR.

1,377,672.

Specification of Letters Patent.

Patented May 10, 1921.

Original application filed June 2, 1913, Serial No. 771,308. Divided and this application filed July 12, 1917. Serial No. 180,193.

To all whom it may concern:

Be it known that I, WILLIAM A. DOBLE, a citizen of the United States, residing at San Francisco, county of San Francisco, 5 and State of California, have invented certain new and useful Improvements in Speed-Governors, of which the following is a specification.

This invention relates to improvements 10 in speed controlling apparatus for motors and more particularly to that class of speed controlling apparatus which is adapted for use in connection with water wheels used for driving electric generators.

15 The invention belongs to that type of speed controlling apparatus in which the speed responsive or governing element controls the gate, or other device for regulating the supply of motive energy, by means of 20 a relay mechanism.

One of the objects of the invention is to provide a mechanism of this class in which the gate or analogous device is moved by fluid pressure means and the controlling 25 or pilot valve for the fluid pressure means is moved in definite relation to the gate so that for every position of the gate there is a corresponding position for the pilot valve.

Another object is to provide an improved 30 form of pilot valve provided with means for limiting the rapidity of the movements of the pilot valve so as to avoid sudden changes in the position of the gate.

Another object of the invention is to provide an improved form of pilot valve which is arranged to automatically close the gate whenever the belt by which the governor 35 is driven breaks or slips off the pulley.

Another object of the invention is to provide an improved means for connecting the gate and the pilot valve, whereby movements of the gate are transmitted to the pilot valve. It has been found difficult in most cases, where speed controlling apparatus is used to place the speed responsive element close to the part from which it is operated and at the same time have the servo-motor in the proper position to operate the gate. In order to obtain the best results it is therefore necessary to separate the speed responsive element from the servo-motor and provide suitable connecting means between the two. By this arrangement the speed responsive element may be

placed close to the shaft from which it is 55 driven and the servo-motor may be located in the proper position to operate the gate in which large power units must necessarily be had a considerable distance from the speed responsive element. In connecting 60 the servo-motor with the speed responsive device cranks and long shafts are undesirable to use on account of possible lost motion which would be detrimental to the correct action of the apparatus. Long belts 65 are also undesirable because of the pulsations which they produce due to the flapping of the belts and in the case of an inertia governor belts could not be used at all. In carrying out my invention the servo-motor 70 is connected with the pilot valve, which is operated by the speed responsive element in such a manner that the movements of the gate are transmitted to the valve by means of balls which are arranged in a tube, 75 the balls acting in substantially the same manner as would a liquid under similar circumstances with the exception that by the use of the balls the disadvantages which would arise from leakage of a liquid are 80 avoided.

Another object of the invention is to provide a speed controlling apparatus of the inertia type by means of which the speed of the motor is controlled by the voltage 85 of the generator driven by the motor and also the load on the generator as well as by variations in the speed of the motor from the normal.

Other objects and the various features of 90 novelty will be apparent from the following description taken in connection with the accompanying drawings, in which:

Figure 1 is a longitudinal section through a water wheel nozzle and the apparatus for 95 controlling the flow through the nozzle.

Fig. 2 is an enlarged sectional view of the pilot valve shown in Fig. 1.

Fig. 3 is an enlarged sectional view of a part of the ball stroke-transmission device.

Fig. 4 is a longitudinal section of another form of speed controlling apparatus.

Fig. 5 is an enlarged vertical section through the speed responsive element shown in Fig. 4.

Fig. 6 is an enlarged view of a detail of 105 the speed responsive element shown in Fig. 4.

Fig. 7 is a section on the line 7—7 of Fig. 4.

Fig. 8 is an enlarged section of the small pilot valve shown in Fig. 4.

5 In this application which is a division of my application #771,308, filed June 2, 1913, I have illustrated a form of speed controlling mechanism which for purposes of illustration is shown in connection with a water 10 wheel, the shaft of the wheel being indicated at 190 and one of the bearings of the shafts being indicated at 191. The wheel is provided with the usual buckets 192 and a casing 193, and a nozzle 194 controlled by a 15 needle valve 195 is arranged to discharge a jet of water against the buckets 192. The nozzle 194 is secured to a nozzle body 196 which may be connected with a suitable supply conduit by means of a flange 197. The 20 needle valve 195 is provided with a stem 198 which extends through a suitable stuffing box 199 carried by the nozzle body.

The speed controlling mechanism about to be described is especially adapted for use 25 in connection with large power units in which the needle valve 195 will be of large size and subjected to heavy pressures and therefore require a comparatively large servo-motor to operate the same. As is 30 usual in such mechanisms I have provided the controlling mechanism with a speed responsive element, and since it is desirable to locate this speed responsive element close to the shaft 190 from which it is driven it 35 must necessarily be at considerable distance from the servo-motor which it controls, and therefore in order to secure regulation as nearly perfect as possible the connections between the speed responsive element and the 40 servo-motor must be such that the movements of the one are transmitted to the other without variation.

In carrying out the invention I provide a servo-motor cylinder 200, in which is arranged a piston 201 and which may be conveniently secured to the nozzle body. A piston rod 202 is secured to the outer end of the stem 198 and passes through the piston 201 and is rigidly connected with the latter. 50 This rod also extends through the head 203 of the cylinder 200 and has a reduced end 204 which carries a piston 205 which is arranged in a dash pot cylinder 206. Leakage from the cylinder 200 along the rod 202 is prevented by means of suitable stuffing boxes 55 207 and 208. A supporting plate 209 is preferably connected with the head 203 of the cylinder 200 and may also be supported by means of a suitable foundation 210.

60 A pair of links 211 engage a pivot 212 carried by a lug 213 on the head 203. The links 211 are connected with a lever 214 by means of a pivot 215. The upper end of the lever 214 is connected with a pivot 216 65 on the rod 202 and a rod 217 is connected

with the lever 214 at a point between the pivots 215 and 216 by means of a pivot 218. The rod 217 passes loosely through apertures in the levers 219 and 220 and is provided with lugs or abutments 221 for these levers. 70 The levers 219 and 220 have their lower ends pivotally connected with the supporting plate 209 and are normally drawn together against the abutments 221 by means of a spring 222. The upper ends of the levers 75 219 and 220 engage the heads of the dash pot cylinder 206. The head 223 of the cylinder 206 is provided with an internally threaded extension 224 which receives the threaded rod 225. A gear wheel 226 is fixed 80 on the rod 225 and in mesh with a pinion 227 on the shaft of a motor 228, the latter being preferably mounted on the dash pot cylinder 206. The rod 225 is provided with a smooth end 227' which is supported by a 85 tubular member 228' carried by a suitable bracket 229 which may be rigidly connected with the supporting plate 209.

The dash pot cylinder 206 is provided with a by-pass 230 which connects the portions of the cylinder which are on opposite sides of the piston 205. This by-pass may be controlled by a suitable valve 231.

Supported on a frame 232 is a valve casing 233 and above the latter and preferably secured thereon is a bracket 234 which carries the speed responsive element. The latter comprises an upright sleeve 235 which is secured to the bracket 234, on which is rotatably arranged a sleeve 236 which carries 95 a bevel gear 237 and a collar 238. Slidably and rotatably arranged on the upper end of the sleeve 235 is a sleeve 239 having a collar 240. Secured to the collars 238 and 240 are springs 241 which carry the centrifugal 100 weights 242. A rod 243 is connected with the sleeve 239 in such manner that the sleeve is permitted to rotate relative to the rod but moves the rod with it as it slides on the sleeve 235. The lower end of the rod 243 110 carries a pilot valve 244 which slides on a tubular extension 245 of a piston 246. The piston 246 is arranged in a suitable bore in the upper part of the valve casing 233 and has a downward extension 247 which is connected with a piston valve 248. The extension 247 passes through a partition 249 which separates the chamber for the piston 246 from the chamber in which the valve 248 is arranged. The valve 248 slides in a sleeve 250 and the latter is slidably arranged 115 in a suitable bore in the casing 233. The sleeve 250 is provided with ports 251, 252 and 253 which register with the annular passages 254, 255 and 256, respectively, in the casing 233. The annular passage 255 has communicating therewith a port 257 which is connected with a supply pipe 258 for the motive fluid for actuating the servo-motor. The annular passage 254 is con- 120 125 130

nected with one end of the servo-motor cylinder 200 by means of a pipe 259 and the passage 256 is connected with the opposite end of the servo-motor cylinder by a pipe 260.

The valve casing 233 is provided with a port 271 which is in communication with the port 257 and the ports 272 and 273. The ports 272 and 273 communicate with the 10 chamber for the piston 246 on opposite sides of said piston. The port 273 is preferably controlled by a valve 274 by means of which the flow through said port may be regulated. A port 275 leads from the chamber for the 15 sleeve 250 to an exhaust pipe 276, whereby water may be discharged from either end of the servo-motor cylinder.

The sleeve 250 has connected therewith a rod 261 which extends through the lower head 262 of the valve casing 233 and is provided on its lower end with an enlarged portion or plunger 263, which is slidably arranged in a cylinder 264 carried by the frame 232. A yoke 265 is secured to the rod 261 above the plunger 263 and has connected therewith a pair of springs 266 which have their lower ends anchored to the frame 232.

The cylinder 264 is also provided with a bore for a plunger 267, this bore being 30 smaller than the bore for the plunger 263, and these two bores are connected by a gradually tapering bore 267'. A pipe 268 has one end connected in alinement with the smaller bore of the cylinder 264 and has its 35 other end extended to and connected in alinement with the bore of the sleeve 228'.

The pipe 268 is suitably curved to avoid sharp bends and is filled with balls 269 which are slightly smaller in diameter than 40 the bore of the pipe. These balls are arranged in contact so that when pressure is applied to one end of the line it will be transmitted directly to the other end. The line of balls extends into the lower end of the cylinder 45 264 and the end ball contacts with the end of the plunger 267. Between the plungers 263 and 267 the cylinder 264 is filled with very small balls 270 as is clearly indicated in the drawings.

50 The operation of the mechanism is as follows:

Assuming that the motor is running at normal speed under a constant load the needle valve 195 will be open sufficiently to 55 discharge the necessary quantity of water to the wheel and the governor which may be driven by a belt 237' from the motor shaft in the usual manner will be rotating with the centrifugal weights 242 in a definite position 60 corresponding to the speed of the motor. Under these conditions the flanges of the piston valve 248 will cover the ports 251 and 253 of the sleeve 250 and thus prevent the motive fluid from the servo-motor from 65 flowing to or from the latter, thus holding

the needle valve 195 in a fixed position. The ports 244' in the pilot valve 244 and the ports 245' in the extension 245 of the piston 246 will also be in registration so that the motive fluid will flow from the port 255 70 through the ports 271 and 273 in the casing 233 and the ports 244' and 245' and the interior of the piston extension 247, the valve 248 and the sleeve 250 to the port 275 and thence into the exhaust pipe 276. This flow 75 of the motive fluid will be restricted by the valve 274 and also by the degree of registration of the ports 244' and 245'. From the drawing it will be seen that the area of the upper side of the piston 246 which is subject 80 to the pressure of the fluid which passes through the port 273, is greater than the area of the lower side of the piston which is subjected to the pressure of the fluid in the port 272. This difference in area and 85 pressure results in the equalization of the load on the opposite sides of the piston and the latter is held stationary.

If for any reason the motor changes in speed the position of the centrifugal weights 90 242 will be changed and the pilot valve 244 raised or lowered. In case the motor speeds up the centrifugal weights will move outwardly and lower the pilot valve 244, and thereby further restrict the flow through the 95 ports 244' and 245'. This will cause the pressure in the chamber above the piston 246 to increase and overbalance the pressure on the lower side of the piston and therefore move the piston and the valve 248 downwardly and uncover the ports 251 and 253 in the sleeve 250. It will be seen that when the valve 248 is lowered the ports 251 will be in communication with the exhaust 276 and the ports 253 will be 100 in communication with the supply pipe 258. The motive fluid will therefore flow through the pipe 260 to one end of the servo-motor cylinder 200 and from the opposite end of the cylinder through the pipe 259 to 105 the exhaust 276. This action will cause the piston 201 and the needle valve to move toward the right and diminish the flow of water through the nozzle 194. By thus 110 diminishing the flow of water through the nozzle the speed of the motor will be restored to normal.

The above described movement of the piston 201 will be transmitted by the rod 204 to the dash pot piston 205. This movement 120 will also be communicated to the upper end of the lever 214 and from the latter a reduced movement will be transmitted to the rod 217. If the change in speed in the motor has been gradual the movement of the piston 205 of the dash pot will cause the fluid in the dash pot to be transferred from one side of the piston to the other by means of the port 230 so that the piston will be 125 permitted to move without directly moving 130

the dash pot cylinder. The latter, however, will be moved by the rod 217 acting through the levers 219 and 220, but it will be observed that, since the movement of the rod 5 217 is less than the movement of the rod 204, the movement of the dash pot cylinder 206 will likewise be less than that of the piston 205. When the rod 204 moves toward the right the lever 219 will be positively moved 10 in the same direction by the abutment 221 with which it is in contact, and the spring 222 will take up the movement of the lever 219 and transmit the same to the lever 220 and the cylinder 206.

15 If the change in speed of the motor has been rapid the piston 201 of the servo-motor will also be quickly moved and, since under these conditions the fluid cannot be transferred from one side of the dash pot 20 cylinder to the other with sufficient rapidity to permit the piston to move independently of the cylinder, it will be seen that the cylinder will be moved with the piston and swing the lever 219 toward the right away 25 from the abutment 221 and thereby extend the spring 222. The action of the spring 222 will, however, gradually move the dash pot cylinder toward the right until the lever 219 contacts with the abutment 221.

30 The motion of the dash pot cylinder is transmitted directly to the rod 225. The springs 266 tend to draw the plunger 263 downwardly, and when the portion 227' of the rod 225 is drawn out of the sleeve 228' 35 by the movement of the dash pot cylinder above described, the pressure of the plunger 263 on the balls 270 will force the latter downwardly into the contracted portion of the cylinder 264 and thus move the line of 40 the balls in the tube 268 so that the end ball in the sleeve 228' will be maintained in contact with the rod 227'.

45 When the speed of the motor is reduced the action of the mechanism will be reversed from that just described and the rod 227' will be moved farther into the sleeve 228', and this motion being transmitted throughout the line of balls in the tube 268 will force the small balls 270 and the plunger 50 upwardly and extend the springs 266.

55 By having the interior of the cylinder 264 of different diameters it will be observed that the mass of small balls therein will act substantially as a liquid and that the movements of the plunger 267 will be greater than the corresponding movements of the plunger 263, the exact ratio of these movements being inversely as the squares of the diameters. The balls therefore act not only 60 to transmit the stroke of the dash pot cylinder, but they also serve as a convenient means for reducing the movement of the plunger 263 corresponding to a given movement of the cylinder 206. The movements 65 of the piston 263 are transmitted to the

sleeve 250 by means of the rod 261, and since the mechanism will move the sleeve in the same direction in which the valve 248 was moved it will be seen that the ports 251 and 253 of the sleeve will be brought into alignment with the flanges of the valve 248 and prevent the fluid from flowing to or from the servo-motor cylinder 200, thus interrupting the movement of the servo-motor piston and holding the latter and the needle valve 75 195 in a fixed position.

70 The normal speed of the motor may be changed by adjusting the valve 274 so as to increase or diminish the flow through the port 273. If the flow through this port is increased the pressure on the upper side of the piston 246 will be increased and the valve 248 moved downward. This will increase the flow through the ports 244' and 245' and thereby equalize the forces acting 85 on the opposite sides of the piston 246, thus holding the latter in a new position. The lowering of the valve 248 will permit fluid to flow from the supply pipe 258 through the ports 252 and 253 of the sleeve and the 90 pipe 260 into the left hand end of the servo-motor cylinder. This will cause the servo-motor piston 201 to move toward the right to slightly close the needle valve 195 and at the same time as above described will lower 95 the sleeve 250 so that the ports 251 and 253 will again be closed by the valve 248. The motor will therefore run at a lower normal speed.

100 When the valve 274 is moved so as to diminish the flow through the port 273 the mechanism will be actuated in the opposite sense and the speed of the motor raised.

105 By means of the motor 228 it is also possible to change the speed of the motor from the switchboard or any other convenient point. The motor 228 will be preferably of the reversible type, whereby the rod 225 may be screwed into or out of the sleeve 224 and thus cause the line of balls in the 110 tube 268 to be moved in one direction or the other. If the rod 225 is screwed out of the sleeve 224 the plunger 263 and the sleeve 250 will be raised and the ports 251 and 253 will be uncovered and fluid permitted 115 to flow through the pipe 260 into the left hand end of the servo-motor cylinder 200, thus effecting a slight closing of the needle valve 195. When the rod 225 is screwed into the sleeve 224 the mechanism will be operated in the opposite direction and the needle valve 195 opened so as to admit an additional supply of water to the motor and thus increase the speed of the latter. It 120 will therefore be seen that the normal speed of the motor may be conveniently regulated from any point by means of the motor 228, or the speed may be regulated by means of the valve 274. Whenever either of these 125 adjusting devices have been set to a given 130

position the mechanism will operate automatically to maintain the speed of the motor at the desired normal. The motor 228 may also be used as a convenient means for starting the motor.

Since the governor and the pilot valve are connected with the servo-motor mechanism only by the pipes 259, 260 and 268 it will be seen that these mechanisms may be placed 10 at considerable distances apart, as may be necessary in properly designing a power plant, and the distance between the mechanisms has no material effect on the sensitiveness of the apparatus.

15 In very large installations the servo-motor assumes a comparatively large size and therefore the pilot valve device for operating the servo-motor must be correspondingly large in order to provide an apparatus of the 20 required sensitiveness. The size of the pilot valves in a large installation is such that they cannot be actuated directly by the speed responsive element and therefore, in the mechanism just described, there is provided 25 a pilot valve device for operating the main pilot valve.

In Figs. 4 to 8 I have shown another form of speed controlling mechanism associated with a water wheel having a shaft 280 and 30 buckets 281. Water is applied to the buckets by means of a nozzle 282 which is controlled by a needle valve 283. The nozzle 282 is secured to the nozzle body 284 and the latter may be secured to a supply conduit by means 35 of a suitable flange 285. The needle valve 283 has a stem 286 which extends through a suitable stuffing box 287 in the wall of the nozzle body 284. A rod 288 is secured to the outer end of the stem 286 and passes 40 through suitable stuffing boxes in the heads of the servo-motor cylinder 289 and is connected with the piston 290. Beyond the servo-motor cylinder 289 the rod 288 has a reduced portion 296' which extends through 45 the head of the dash pot cylinder 292 and is connected with the dash pot piston 293.

The servo-motor cylinder 289 is preferably secured to the nozzle body 284 and a supporting plate 294. The plate 294 carries a 50 bracket 295, to which the lever 296 is connected by means of a pivot 297. The pivot 297 is adjustable in a suitable slot in the lever 296 and is also adapted to slide in a slot 298 in the bracket 295. The upper end 55 of the lever 296 is connected with the rod 288 by means of a pivot 299. A rod 300 has one end connected with the lever 296 by means of a pivot 301 and has its other end bifurcated and connected with an arm 302 60 by means of a pivot 303. The arm 302 is carried by a shaft 304 which is mounted in suitable brackets 305 on the supporting plate 294.

A rod 306 is connected with the dash pot 65 cylinder 292 and extends into a sleeve 307

carried by a bracket 308 on the supporting plate 294. The rod 306 is provided with an abutment 309 which is arranged between a pair of levers 310 and 311, the latter being pivotally mounted on the shaft 304. The 70 upper ends of the levers 310 and 311 are connected together by means of a retractile spring 312. The pivot pin 303 carries a block 313 which is also arranged between the levers 310 and 311 and engaged thereby. 75

A frame 314 supports a pilot valve casing 315, in which is arranged a sleeve valve 316 and a piston valve 317, these valves co-operating to control the servo-motor. The sleeve 316 is connected with a rod 318 which projects through the lower head of the casing 315 and has on its lower end a plunger 319 which is arranged in a cylinder 320. The lower end of the cylinder 320 is provided with a bore in which is arranged a plunger 80 321 of considerably smaller diameter than the plunger 319. The space between the plungers 319 and 321 is filled with very small balls 322, the latter acting in the manner of a liquid to transmit the movements of one of the plungers to the other.

A pipe 323 has one end connected with the cylinder 320 in alinement with the bore in the lower end thereof and has its other end connected with the sleeve 307 in alinement 85 with the bore in the latter, thus forming a continuous conduit between the interior of the cylinder 320 and the sleeve 307. The space in this conduit between the end of the rod 306 and the lower end of the plunger 321 is filled with balls 324 which are slightly smaller in diameter than the interior of the pipe, whereby they are adapted to move freely in the latter. The arrangement of the balls 322, the plunger 321 and the balls 100 324 constitute a means for rigidly connecting the plunger 319 and the rod 306, whereby the movements of one are transmitted to the other, this construction being, preferably 105 the same as shown in Figs. 1 and 3 and described hereinabove. 110

A yoke 325 is arranged on the rod 318 and has connected therewith a pair of springs 326, the lower ends of these springs being anchored to the frame 314. The 115 means for controlling the servo-motor is similar to that shown in Figs. 1 and 2 and comprises the casing 315 which is provided with the annular passages 327, 328 and 329, the passage 327 being connected with one 120 end of the servo-motor cylinder 289 by means of a pipe 330 and the passage 329 being connected with the opposite end of the servo-motor cylinder by means of a pipe 331. The sleeve 315 is provided with ports 125 327', 328' and 329' which register respectively with the passages 327, 328 and 329. The passage 328 is connected with a supply pipe 332, for the motive fluid for actuating the servo-motor, by means of a port 333. 130

The casing 315 is preferably made in two sections and the upper section thereof has arranged therein a piston 334 which is connected with the valve 317 by means of a tubular extension 335. A port 336 leads from the port 333 and has a branch 337 whereby the pressure of the supply fluid is transmitted to the space below the piston 334. A port 338 connects the port 336 with the space above the piston 334 and is controlled by means of a valve 339.

The piston 334 has an upward extension 340 having ports 341 therein and a pilot valve 342 is slidably arranged on the exterior of this extension. The valve 342 is provided with suitable ports 343 adapted to register with the ports 341 in the extension 340.

The dash pot cylinder 292 is provided with a port 344 connecting the opposite ends of the cylinder and controlled by means of a suitable valve 345. In the operation of the dash pot the cylinder is maintained full of oil, or other suitable fluid, which is transferred from one side of the piston to the other by means of the movements of the piston, the rate of flow of the oil being regulated by means of the valve 345.

The operation of the mechanism so far described is as follows:

The pilot valve 342 is connected with and controlled by a governing mechanism which will be described later, and the movements of this valve, in response to the action of the governing mechanism, produce corresponding movements in the needle valve 283 and thus regulate the supply of water to the wheel.

Assuming that the wheel is running at normal speed under a steady load, the valve 283 will stand open a sufficient extent to supply the necessary amount of water and the ports 343 in the pivot valve 342 will to a certain extent be in registration with the ports 341 in the extension 340 of the piston 334. The area of the upper side of the piston 334 is considerably larger than the area of the lower side thereof as will be readily seen from the drawings so that the force tending to move the piston upward, due to the pressure in the port 336, will be counterbalanced by a higher pressure on the upper side of the piston. Since the fluid which is supplied to the chamber above the piston passes through the port 338 and its flow is restricted by means of the valve 339 it will be seen that the pressure in the chamber above the piston will be controlled by the extent to which the ports 341 and 343 are in registration. The fluid passing through these ports will pass downwardly through the piston and the valve 317 into the chamber at the lower end of the valve casing and be discharged from the latter by means of a suitable exhaust pipe 347.

If for any reason the pilot valve 342 is lowered by the governing mechanism, the ports 343 will be moved farther out of registration with the ports 341 and therefore so restrict the flow of fluid through these ports that the pressure in the chamber above the piston 334 will be increased and thereby overbalance the pressure acting on the lower side of the piston and move the latter downwardly. Since the valve 317 is connected with the piston 334 the valve will also be moved downwardly and uncover the ports 327' and 329' putting the former in communication with the exhaust pipe 347 and the latter in communication with the supply pipe 332. The pressure fluid will therefore be admitted to one end of the servomotor cylinder through the pipe 331 and be discharged from the other end of the cylinder by means of the pipe 330. This will cause the piston 290 to be moved in the direction to close the needle valve 283, thereby diminishing the flow of water through the nozzle 282 and reducing the speed of the wheel.

When the pilot valve 342 is raised by the governing mechanism the ports 341 and 343 will be brought into fuller registration and thereby decrease the pressure in the chamber above the piston 334 and cause the latter to be moved upwardly by the pressure acting on the lower side of the piston. The valve 317 will thus be raised and the ports 327' and 329' again uncovered. In this instance, however, the ports 329' are put into communication with the exhaust pipe 347 and the ports 327' are put into communication with the supply pipe 332, thus supplying the pressure fluid through the pipe 330 to the opposite end of the servomotor cylinder and thereby further opening the needle valve 283 and permitting an increased quantity of water to flow through the nozzle 282 and increase the speed of the wheel.

If the pilot valve 342 is moved gradually the servomotor piston 290 will also be moved gradually and since the dash pot piston 293 is rigidly connected with the servomotor piston the dash pot piston will be moved in the direction of movement of the servomotor piston and at exactly the same speed so that the fluid in the dash pot cylinder will be transferred from one end of the cylinder to the other without causing the dash pot cylinder to be moved directly by its piston. Under these circumstances the dash pot cylinder will be moved by the rod 300 and the levers 310 and 311; the spring 312 being strong enough to accomplish a circulation of the fluid in the dash pot around the piston 293. If, however, the pilot valve is shifted quickly for any reason, the movement of the dash pot piston will be correspondingly rapid and in this case the restriction of the flow of fluid from one end

of the dash pot cylinder to the other will not allow the fluid to be transferred as rapidly as the piston moves and therefore the dash pot cylinder will be moved directly 5 with the piston.

From Fig. 4 it will be obvious that the rod 300 will move simultaneously with the rod 288, but the length of movement will be considerably shorter owing to the fact

- 10 that the distance between the pivots 297 and 301 is only a fraction of the distance between the pivots 297 and 299. The movements of the rod 300 are transmitted to the pair of levers 310 and 311 and from the latter to the rod 306. If the rod 306 is moved into the sleeve 307 the line of balls 324 will be forced up into the cylinder 320 and raise the plunger 319 and the sleeve 316 which is connected therewith, and if the rod 306 is 20 drawn outwardly in the sleeve 307 the movement of the sleeve 316 will be in the opposite direction. Owing to the difference in areas of the plungers 319 and 321 it will be obvious that the plunger 319 will be moved 25 only a fraction of the distance to which the plunger 321 is moved, the exact ratio of the movements being in proportion to the squares of their diameters. In every instance the movement of the sleeve 316 will 30 be in the same direction as the corresponding movement of the valve 317 and therefore the ports 327' and 329' will be closed by the movement of the sleeve and the movement of the servo-motor piston interrupted. 35 By this arrangement the servo-motor piston will have a position corresponding to every position of the valve 317.

When the movement of the servo-motor piston is gradual the dash pot cylinder is 40 moved by means of the levers 310 and 311, but when the movement of the servo-motor piston is rapid the dash pot cylinder will be moved directly by the dash pot piston and the spring 312 take up any inequalities in 45 the movements and eventually restore the parts to their proper position.

For the purpose of actuating the pilot valve 342 I have provided a mechanism which is responsive to changes of speed of 50 the motor, to changes of voltage of the generator driven by the motor and to changes in the current output of the generator. This mechanism comprises a shaft 350 which is mounted in bearings 351 and 55 352 carried by a table 353 which is preferably supported on the upper end of the pilot valve casing 315. The shaft 350 is provided with a driving pulley 354 by means of which it may be driven from the 60 motor shaft by a belt 355. A fly wheel 356 has a threaded bore which engages the screw threads 350' on the shaft 350 and is connected with a collar 357 which is rigidly secured to the shaft 350 by means of a helical spring 358 surrounding the shaft. A

bell crank 359 is mounted on a pivot 360 carried by brackets 361 on the table 353, and has one arm provided with a yoke 362 having trunnions which engage a suitable groove 363 in the hub of the fly wheel 356. 70 The other arm of the bell crank is connected with the upper end of a rod 364 by means of links 365. The lower end of the rod 364 is secured to the pilot valve 342.

A solenoid consisting of the coils 366 and 75 367 and the core 368 is mounted on the table 353 beneath the fly wheel 356. Pole pieces 369 and 370 are secured to the ends of the core 368 and have upwardly extending portions with curved inner faces arranged adjacent the periphery of the fly wheel 356. 80 These curved faces of the pole pieces and the periphery of the fly wheel 356 are provided with the serrations 371 and 372 respectively. 85

The generator which is driven by the motor is diagrammatically shown and indicated at G. The main conductors of the generator G are indicated by the numerals 373 and 374. The conductors 375 and 376 90 lead to the solenoid coil 367 and in one of these conductors is arranged a suitable adjustable resistance 377. A resistance 378 is arranged in the conductor 374 so that the current generated will pass through this 95 resistance. The terminals of the resistance 378 are connected with the solenoid coil 366 by means of the conductors 379 and 380.

A bracket 381 is secured to the pole piece 369 and carries an electromagnet 382, the 100 armature 383 of which is pivoted at 384 and rigidly connected with a brake shoe 385. A spring 386 tends to swing the brake shoe 385 into contact with the periphery of the wheel 356. The terminals of the electromagnet 382 are connected with the conductors 373 and 374 by means of the conductors 387 and 388. 105

The operation of the governing mechanism is as follows:

The shaft 350 being driven from the motor shaft 280 will have a speed at all times in direct proportion to the speed of the latter and the fly wheel 356 will be normally driven at the same speed as the shaft 110 115 by means of the spring 358. If the motor increases in speed, for any reason, the speed of the shaft 350 will be correspondingly increased and the inertia of the fly wheel 356 will cause the latter to lag somewhat behind the shaft, the difference in speed being taken up by the spring 358. This lagging of the fly-wheel 356 which results in the shaft 350 rotating relative to the fly wheel causes the latter to be moved endwise of 120 the shaft on account of the screw threaded connection therewith. The direction of rotation of the shaft 350 is indicated by the arrow at the end thereof and from this and the description of the screw threads it will 125 130

be seen that when the fly wheel lags behind the shaft it will be moved toward the right, Fig. 5, and thus rock the bell crank 359 so as to lower the pilot valve 342. The lowering of the pilot valve as has been described causes the needle valve 283 to be moved toward the closed position, thereby reducing the supply of water to the motor and causing a reduction in the speed of the motor.

10 If on the other hand the motor slows down in speed the fly wheel 356 will have a tendency to continue at the high speed of rotation and will therefore move endwise on the shaft 350 toward the left, Fig. 5. This 15 will cause the pilot valve 342 to be raised and thus effect an opening of the needle valve 283 in the manner hereinbefore described.

Since the coil 367 of the solenoid is connected directly across the terminals of the generator it will be seen that the current flowing through the coil will be in accordance with the voltage of the generator, it being understood of course that the resistance 377 remains constant. The purpose of this resistance is to regulate the current which is supplied to the coil 367. The coil 367 magnetizes the pole pieces 369 and 370, which have a retarding effect upon the fly wheel 356, the serrations in the periphery of the fly wheel and on the faces of the pole pieces being for the purpose of accentuating this retarding effect. As the retardation of the fly wheel is directly proportional to the circumferential speed of the fly wheel the position of the wheel on the shaft 350 will be determined by its speed and therefore if the voltage either rises or falls the retardation will be effected and the wheel rotated in 30 one direction or the other relative to the shaft 350. This relative rotation will cause the wheel to be moved endwise of the shaft and actuate the pilot valve 342. The arrangement of the parts is such that an increase in voltage will move the fly wheel toward the right and diminish the supply of water to the wheel and thereby reduce its speed, and a decrease in voltage will permit the spring 358 to rotate the wheel relative to the shaft 40 so that it will be moved toward the left and thereby raise the pilot valve 342 and increase the supply of water to the wheel.

The coil 366 of the solenoid which is connected to the terminals of the resistance 378 acts differentially with respect to the coil 367. When the current through the conductors 373 and 374 increases the current in the coil 366 will be correspondingly increased 55 and the magnetic effect due to the coil 367 diminished, thus reducing the retardation of the wheel 356. This permits the wheel to be rotated on the shaft 350 by the spring 358 and thus move toward the left and cause the needle valve to be further opened to increase

the speed of the motor. Similarly a decrease in the current flowing in the conductors 373 and 374 will decrease the current in the coil 366 and diminish the differential action of the latter and thereby increase the magnetic effect of the coil 367 and the retarding action on the wheel 356 due thereto. This will cause the wheel to be further retarded with respect to the shaft 350 and move toward the right and effect a closing action of the 75 needle valve 383.

If for any reason current should cease to flow from the generator the electro magnet 382 would be demagnetized and the spring 386 would throw the brake 385 into engagement with the periphery of the fly wheel 356 and prevent the latter from moving in the direction to open the needle valve and would therefore prevent over-speeding of the motor.

85 In the normal operation of the generator the changes in load may be manifested by changes in voltage and in the current output, and therefore it will be seen that the governing mechanism which I have devised 90 will be responsive to these changes and operate the needle valve to vary the quantity of water supplied to the wheel before the wheel has changed in speed as a result of the change in load. If, however, the generator is suddenly subjected to a very large 95 change in load the magnetic action on the fly wheel 356 would not be effective enough and a change in the speed of the motor would take place. Under these circumstances the change in speed of the motor brings into action the inertia effect of the fly wheel 356 and the needle valve is shifted in the required direction an amount corresponding to the change in speed. On account of the masses of the needle valve the parts connected therewith and also the masses of the pressure fluid in the pipes 330 and 331 a certain time would elapse before 100 the effect of the governing action would be 105 produced at the wheel, unless means were provided for obviating this delay, and therefore over-regulation or racing would take place. I avoid overgoverning or racing by introducing the dash pot device in the connection with the servo-motor piston and the rod 306 and as a result of the action of this dash pot the stroke of the valve sleeve 316 is 110 for the first instant of governing larger than is required to have the servo-motor piston 115 move in proportion to the movement of the valve 317. In case of a rapid movement of the servo-motor piston the dash pot fluid cannot pass through the port 344 rapidly enough and therefore an excess of pressure 120 will be created on one side of the dash pot piston which will cause the dash pot cylinder to follow the stroke of the piston against the tension of the spring 312, but the spring 125 will afterward bring the dash pot cylinder 130

back to its final position according to the stroke of the rod 300.

Having thus described the invention what is claimed and desired to be secured by Letters Patent is:

1. In an apparatus of the class described, the combination of a controlling element, means for automatically operating said controlling element, and comprising a member 10 movable in accordance with the movement of said controlling element, and means for so moving said member comprising a conduit and a series of contacting rigid bodies in said conduit adapted to be moved longitudinally thereof as a unit.
2. In an apparatus of the class described, the combination of a controlling element, means for automatically operating said controlling element and comprising a member 20 movable in accordance with the movements of said controlling element, and means for so moving said member and comprising a conduit having portions of different internal diameters and a series of contacting 25 rigid bodies arranged in said conduit, said bodies being of different sizes with the smaller of said bodies arranged in the portion of said conduit having the larger internal diameter.
3. In an apparatus of the class described, the combination of a controlling element and means for operating said controlling element, and comprising a motor, and means for controlling said motor including a conduit 30 and a series of contacting rigid bodies in said conduit adapted to be moved as a unit to actuate a portion of said controlling means.
4. In an apparatus of the class described, 40 the combination of a controlling element, means for automatically operating said controlling element, including a member adapted to be moved in accordance with the movements of said controlling element, and means for so moving said member comprising a conduit having portions of different internal diameters and a series of contacting rigid bodies arranged in said conduit, said bodies being of different sizes and the 45 smaller size being arranged in the portion of the conduit having a larger internal diameter, a plunger connected with said member and arranged within the portion of the conduit having a larger internal diameter, 50 whereby the plunger is adapted to be moved longitudinally of said conduit by said bodies.
5. In an apparatus of the class described, 60 the combination of a controlling element, means for operating said controlling element, and means for automatically controlling said operating means and including a member movable in accordance with the movement of said controlling element, a 65 conduit, a plunger connected with said mem-

ber and arranged at one end of said conduit, means normally tending to move said plunger into said conduit, a plunger at the opposite end of said conduit, a series of contacting rigid bodies arranged in said conduit 70 between said plungers whereby the movement of one plunger is transmitted directly to the other, and means whereby the second plunger is moved by said controlling element.

6. In an apparatus of the class described, the combination of a controlling element, means for operating said controlling element, and means for controlling said operating means and including a member movable 80 in accordance with the movement of said controlling element, a conduit, a plunger connected with said member and arranged in one end of said conduit, means normally tending to move said plunger into said conduit, a plunger at the other end of said conduit, a series of contacting rigid bodies arranged in said conduit, with the end members of said series engaging said plungers, and means connecting said second plunger 85 and said controlling element and adapted to move said plunger directly with said controlling element when the latter moves rapidly and to move said plunger indirectly from said element when the latter moves 90 slowly.

7. In an apparatus of the class described, the combination of a controlling element, means for operating said controlling element, and means for automatically controlling said operating means and including a member movable in accordance with the movements of the controlling element, a conduit having its end portions of different internal diameters, a plunger connected directly with said member and arranged in the larger end of said conduit, a second plunger arranged in the smaller end of said conduit and connected with said controlling element, a series of contacting rigid bodies 100 arranged in said conduit between said plungers, said bodies being of different sizes with the smaller size arranged in the portion of the conduit having the larger internal diameter, and means normally tending 105 to move said first plunger into said conduit.

8. In an apparatus of the class described, the combination of a controlling element, means for operating said controlling element, and means for automatically controlling said operating means and comprising a member movable in accordance with the movements of said controlling element, and means for so moving said member and comprising a dash-pot device adapted to move 110 said member directly with said controlling element when the latter moves rapidly and indirectly and to a less distance when the controlling element moves slowly.

9. In an apparatus of the class described, 130

the combination of a controlling element, means for operating said controlling element and means for automatically controlling said operating means, and including a member movable in accordance with the movements of the controlling element and an adjustable dash-pot device adapted to move said member directly with the controlling element when the latter moves rapidly 5 and indirectly and to a less extent when the controlling element moves slowly.

10. In an apparatus of the class described, the combination of a controlling element, means for operating said controlling element, and means for automatically controlling said operating means and including a member movable in accordance with the movements of the controlling element and means connecting said member and said 15 controlling element and including two telescopic members, and means adapted to be controlled from a distance for moving one of said telescopic members into or out of the other.

20. 11. In an apparatus of the class described, the combination of a controlling element, means for operating said controlling element, and means for automatically controlling said operating means, and including a member movable in accordance with the movements of said controlling element, and means for connecting said member with said controlling element and including a dash-pot having a cylinder and piston, means 25 connecting one of the elements of the dash-pot with the controlling element, means connecting the other of the elements of the dash-pot with said member, a pair of levers mounted on fixed pivots and normally engaging 30 the part movable with said member, spring means for normally holding said levers against said part and a rod connected with said element and adapted to move one of said levers directly with the controlling 35 element when the latter moves in one direction and the other lever directly with the controlling element when the latter moves to the opposite direction.

40. 12. In an apparatus of the class described, the combination of a controlling element, means for operating said controlling element and means for automatically controlling said operating means and including a member movable in accordance with the 45 movements of said element and means for moving said member and including a dash-pot having a cylinder and piston, a rod connecting said piston directly with said controlling element, means connecting the dash-pot cylinder with said member, whereby the member is moved in accordance with the movements of the dash-pot cylinder, a lever pivotally connected with said rod, a pair of levers having a fixed pivot and arranged 55 to be swung with movement of the dash-

60 pot cylinder, spring means normally tending to draw said levers together, and a rod pivotally connected with said first mentioned lever and so connected with said pair of levers that one of said pair of levers is positively moved by the rod when the latter moves in one direction and the other of said levers is positively moved by the rod when the latter moves in the latter direction.

13. In an apparatus of the class described, 75 the combination of a controlling element, means for operating said controlling element, and means for controlling said operating means and including a member movable in accordance with the movements of 80 the controlling element, and a member co-operating therewith, a piston connected with said second member and adapted to move the same, means for supplying fluid pressure to the opposite sides of said piston, and 85 means for regulating the pressure on one side of said piston so as to move the latter by the difference in pressure on the two sides thereof.

14. In an apparatus of the class described, 90 the combination of a controlling element, means for operating said controlling element and means for controlling said operating means and including a member movable in accordance with the movements of the 95 controlling element, and a member co-operating therewith, a piston connected with said second mentioned member and adapted to move the same, means for supplying fluid pressure to the opposite sides of said piston, 100 means for discharging the pressure fluid from one side, and means for regulating said discharging means so as to move the piston by the difference in the pressure on the two sides thereof.

15. In an apparatus of the class described, 105 the combination of a controlling element, means for operating said controlling element, and means for controlling said operating means and including a member movable in accordance with the movements of the controlling element, and a second member co-operating therewith, a cylinder, a piston in said cylinder and connected with said second member for moving the latter, one 110 side of said piston being of greater area than the other, means for supplying fluid pressure to the opposite sides of said piston, means for discharging the pressure fluid from the larger side of said piston, and 115 means for automatically regulating said discharging means to control the pressure on the larger side of the piston.

16. In an apparatus of the class described, 120 the combination of a controlling element, 125 means for operating said controlling element, and means for controlling said operating means and including a member movable in accordance with the movements of the controlling element, and a second mem- 130

ber coöperating therewith, a cylinder, a piston in said cylinder and connected with said second member for operating the latter, one side of said piston being of larger area than the other, a tubular extension on the larger side of said piston, means for supplying fluid pressure to the opposite sides of said piston, and means coöperating with said tubular extension to control the pressure on the larger side of the piston.

17. In an apparatus of the class described, the combination of a controlling element, means for operating said controlling element, and means for controlling said operating means and including a member mov-

able in accordance with the movements of the controlling element, and a second member coöperating therewith, a cylinder, a piston in said cylinder and connected with said second member for operating the latter, said piston being of larger area on one side than the other, a tubular extension on the larger side of said piston, means for supplying fluid pressure to the opposite sides of said piston, a sleeve slidable on said tubular extension and coöperating therewith to control the pressure on the larger side of said piston, and means for moving said sleeve.

In testimony whereof I affix my signature.

WILLIAM A. DOBLE.
